United States Patent Office

Des. 221,067
Patented July 6, 1971

221,067

BUILDING

Jack R. Butz, Tulsa, Okla., assignor to
John K. Selby, Tulsa, Okla.

Filed Nov. 24, 1969, Ser. No. 20,257

Term of patent 14 years

Int. Cl. D25—04

U.S. Cl. D13—1

FIG. 3

FIG. 4

FIG. 1 is a front elevational view of the building showing my new design.

FIG. 2 is a rear elevational view thereof.

FIG. 3 is a right side elevational view thereof.

FIG. 4 is a left side elevational view thereof.

I claim:

The ornamental design for a building, substantially as shown and described.
